SEWING MACHINE

Joseph H. Pikul, West Newton, Mass., assignor to
The Reece Corporation, a corporation of Maine

Application April 19, 1944, Serial No. 531,706

11 Claims. (Cl. 112—242)

1
This invention relates to sewing machines and more particularly to the thread-handling mechanisms thereof.

It is an imperative requirement of any modern sewing machine that a stitch is being formed with the first reciprocation of the needle in an operating cycle of the machine. To attain this end, it is customary to provide a thread pull-off which draws extra thread from the thread supply and makes it available to the needle for the formation of the first stitch, so that the thread end will remain in the work and not be pulled therethrough by the action of the stitch-forming instrumentalities. The conventional thread pull-offs, however, lack control over the extra thread and leave the same dangling on the machine for use by the needle, with the result that at least the first stitch is loose and irregular in appearance as compared with the subsequent stitches.

It is the primary aim and object of the present invention to provide in a sewing machine a thread pull-off which controls the extra thread drawn from a thread supply, to the end that the extra thread provided is at no time appreciably slackened and is made available to the needle substantially at the rate at which the latter requires it for the formation of the first stitch.

The invention will best be understood from the following description of an illustrative embodiment thereof shown in the accompanying drawings, in which

Fig. 1 is a fragmentary side elevation, partly in section, of a sewing machine embodying the present invention.

Fig. 2 is a fragmentary section, taken on the line 2—2 of Fig. 1.

Fig. 3 is an enlarged, fragmentary front elevation, partly in section, of the machine.

Fig. 4 is an enlarged, fragmentary section, taken on the line 4—4 of Fig. 1.

Figs. 5 and 6 are fragmentary side elevations, partly in section, of the machine, showing certain cooperating elements in different positions of operation.

Figs. 7 to 10, inclusive, are fragmentary side elevations of the machine similar to Figs. 5 and 6, and showing certain cooperating elements in different positions of operation.

Fig. 11 is a front elevation of the looper mechanism employed in the present machine; and

Fig. 12 is a front elevation of the same looper mechanism in a different operating position.

While the invention is not limited in its application to any particular type of sewing machine, it is for convenience illustrated in connection with

2
a button sewing machine of the character shown and described in U. S. Letters Patent No. 2,158,171, issued May 16, 1939. This machine has a base 15 supporting a work plate 16, and an overhanging head 17 in which is suitably guided a needle bar 18, carrying a needle 19 which cooperates with underthread or looper mechanism 20, including loopers 21 and loop spreaders 21a (Fig. 11), to attach to work W supported on the work plate 16 a flat perforated button B held by a combined presser foot and clamp assembly C. The construction of the combined presser foot and clamp assembly does not form a part of the present invention, and is for this reason not described in detail herein.

The assembly C is carried by an arm 22 which extends from a rod 23 slidably secured, as by bearings 24, to the outside of the casing (Fig. 3). The rod 23 carries a pin 25 engaged by a yoke 20, formed in one arm 27 of a lever 28 which is mounted on a rock shaft 29, extending through the head 17 and journalled in the walls of the head (Figs. 1 and 2). A torsion spring 30 normally urges the shaft in a counter-clockwise direction as viewed in Fig. 1 to maintain the assembly C in its lowermost or work clamping position. The other arm 31 of the lever 28 is connected by suitable linkage 32 with a treadle 33. When the treadle 33 is depressed, the lever 28 and shaft 29 are rocked clockwise as viewed in Fig. 1, raising the rod 23 and the assembly C.

The looper mechanism 20 is mounted on a shaft 34, driven by suitable means (not shown) which oscillates said looper mechanism in timed relation with the needle reciprocations. The needle bar 18 is reciprocated longitudinally by mechanism including a crank 35 (Fig. 2), connected to the needle bar by a link 36. The crank 35 is secured to a needle shaft 37, driven by means (not shown) which are, or may be, similar to those described in Patent No. 2,158,171.

In the present machine, the thread *t* passes from a needle thread supply (not shown) to the needle 19 through a permanent thread tension 38 and a controlled thread clamp 40, as well as through a stitch-setting member 45 on the head of the machine and a thread tension 39 on the needle bar 18. The thread also passes over pins 41 and 41a on the head 17. The tension 38 prevents an over-draft of the thread from the supply, and the tension 39 is relatively light and serves to hold the thread taut between itself and the needle eye. The thread clamp 40 is normally closed to prevent the passage of thread, but is held open during a part of each work-penetrating

stroke of the needle by a cam 42 (Fig. 3) which is carried by the needle crank 35. The cam 42 is adapted to depress a plunger 43 in the wall of the head 17 against the tension of a spring 44 which normally holds the clamp 40 closed. Such depression of the plunger 43 opens the clamp 40 and permits the needle to draw through it an amount of thread adequate for the formation of each stitch. The stitch-setting member 45 is provided at its free end with an eye 46 through which the thread passes, and is adjustably secured by a screw 47 to one side of the head 17 at a point between the needle-bar tension 39 and the clamp 40.

In accordance with the present invention, a curved arm 50 is secured to the outer end of a rock shaft 51 which is journaled in a bearing 52 in the head of the machine. A slot or thread passage 53 is formed in a lateral lug 54 of the arm 50, and a member 55, having an eye or thread passage 56, is adjustably secured to said arm 50 by means of a screw 58 which extends through a slot 57 in the member 55 and is threaded in said arm 50.

Mounted on the inner end of the rock shaft 51 is an arm 59, carrying at its free end a laterally projecting pin 60, normally adapted to be received in a notch 61 in a latch lever 62, pivoted at 63 to the wall of the head 17 and urged in a clockwise direction as viewed in Fig. 1 by a tension spring 64. A laterally projecting pin 65 on the latch lever 62 is adapted to be engaged by a radial finger 66, secured on the rock shaft 29. A link 67 (Fig. 4) connects the arm 59 with a lever 68, pivoted at 69 to the head 17 of the machine and having intermediate its ends a cam follower 70 adapted to cooperate with a cam 71 on the needle shaft 31. A suitably mounted torsion spring 72 (Figs. 1 and 2) urges the arm 59 in a counter-clockwise direction as viewed in Fig. 1 and, through intermediation of the arm 59 and link 67, urges the follower 70 of the lever 68 against the cam 71.

After the machine has concluded a sewing operation, the operator depresses the treadle 33 so as to lift the assembly C and permit the removal of the work. New work may then be inserted in the machine, whereupon the assembly C is lowered by releasing the treadle 33. In lifting the assembly C as described, the finger 66 on the rock shaft 29 engages the pin 65 on the latch lever 62 and swings the latter from the position shown in Fig. 5 into that shown in Fig. 6, thereby releasing the pin 60 on the arm 59 and permitting the arm 50 to swing from the home position shown in Fig. 5 into the intermediate position shown in Fig. 6, while the lever 68 is moved from the dot-and-dash line position into the full line position shown in Fig. 4, i. e., into engagement with the cam 71. The swing of the arm 50 from home position into the intermediate position (Fig. 6) is relatively short and insufficient to pull extra thread from the supply.

The machine is now ready to be started, and the cam 71 will, on rotation in the direction of the arrow 71a (Fig. 4) and during the first descent of the needle 19 from its uppermost position (Fig. 5) into the intermediate position 19' (Fig. 1), lower the arm 50 from the intermediate position shown in Fig. 6 into the lowermost position shown in Fig. 1. While the arm 50 is thus lowered, the thread passage 53 in the latter will draw extra thread from the thread supply through the tension 38 and to one side of the closed clamp 40, while the thread passage 56 in the member 55 will be lowered so as to permit

a partial collapse of the thread between the closed clamp 40 and needle bar tension 39. However, the member 55 is preferably so adjusted on the arm 50 that the resulting slack in the thread between the clamp 40 and needle bar tension 39 is created not appreciably in excess of the rate at which the descending needle will use up said slack without withdrawing thread through the needle eye. During further descent of the needle 19 from the position 19' (Fig. 1) into the position 19'' (Fig. 9), the cam 42 opens the thread clamp 40 and the cam 71 retracts the arm 50 from the lowermost position shown in Fig. 1 into the intermediate position shown in Fig. 9, whereby the thread passage 53 in said arm 50 releases the extra thread previously drawn from the supply to the open thread clamp 40, and said released thread is drawn through said open clamp by the tension 39 and the force with which the thread is frictionally retained on the needle when the same passes through the work W. When the needle 19 reaches the position 19'' in Fig. 9, the cam 42 clears the plunger 43 of the thread clamp 40 and the latter is permitted to close, with the result that the thread between the clamp 40 and the eye of the needle 19 is, during the last part of the descent of the needle from the position 19'' into the lowermost position 19''' (see dot-and-dash line position in Fig. 9), sufficiently tensioned to assure that a thread loop l is being cast by the needle on its following ascent. When the needle reaches its lowermost position, a substantial length of the thread end beyond the needle eye projects from one of the holes in the button B, and most of this projecting thread length is subsequently withdrawn through said hole during the seizure and deflection of the loop l by one of the loopers and the cooperating loop spreader of the looper mechanism 20 (Fig. 10). As the needle 19 ascends from its lowermost position into the uppermost position, the needle thread between the work and the stitch-setting member 45 is merely deflected by the needle bar tension 39 whose thread-clamping force is insufficient to draw the thread end through the work. Shortly before the needle reaches its uppermost position, the cam 71 returns the arm 50 from the intermediate position shown in Fig. 10 into the home position shown in Fig. 5, whereby the thread passage 56 in the member 55 slightly retracts the needle thread through the eye of the needle 19 to the extent that the thread end is withdrawn below the top surface of the button B but remains in the work W (Fig. 11). When the arm 50 is returned to home position, the latch lever 62 is permitted to return to latching position (Fig. 5) and the arm 50 is latched in home or inactive position during the remainder of the operating cycle of the machine, though its actuating cam 71 turns with the needle shaft 37 throughout the remainder of said operating cycle. More particularly, the arm 50 is returned to home position when the crest c of the cam 71 (Fig. 4) is opposite the follower 70 on the lever 68. This cam crest c is immediately followed by a cam descent d, the point e of which is opposite the follower 70 in the intermediate position of the cam 71 so that said follower may rise into engagement with the cam point e and permit the arm 50 to move into the intermediate position shown in Fig. 6 on being unlatched in home position when the operator raises the clamp assembly C, as described. While the left hand looper 21 and spreader 21a hold the loop l deflected as shown in Fig. 11, the needle again de-

scends, through the other hole in the button B, however, and enters the deflected loop l. After the needle 19 has entered the deflected loop l and before it reaches its lowermost position, the looper mechanism 20 is rocked counterclockwise as viewed in Fig. 11 until the left hand looper 21 and spreader 21a clear the loop l. Thereafter, continued downward movement of the needle 19 into its lowermost position will result in slight contraction of the loop l (Fig. 12) due to withdrawal of thread therefrom by the needle, all the extra thread being used up and the thread between the clamp 40 and the needle being taut at this time. Thus, the loop l is sufficiently contracted to be out of the way of the right hand looper 21 and spreader 21a when the same seize the loop l' cast by the needle on its following ascent (Fig. 12). The stitch-setting member 45 is so angularly adjusted on the machine head 17 that the thread between the work W and the clamp 40 is, during the last part of the ascent of the needle on each following reciprocation in the operating cycle of the machine, sufficiently deflected by the needle bar tension 39 to impose tension on said thread and thereby set each stitch. Also, after the needle 19 has entered the deflected loop held by a looper and cooperating loop spreader and before the needle reaches its lowermost position on each following descent, the deflected loop is released from its looper and spreader and the needle will then, on continued movement into lowermost position, withdraw sufficient thread from the released loop to contract the latter out of the way of the other looper and spreader which will seize the next loop.

Since the arm 50 is adjustably mounted on the rock shaft 51, preferably by being clamped thereon as at 101 (Figs. 1 and 2) and the member 55 is adjustable on the arm 50 as explained, the needle thread in the machine may, for the successful formation of the first stitch in each operating cycle, be regulated to suit most any conceivable sewing condition. By properly designing the cam 71 and properly adjusting the arm 50 and member 55, the condition is readily attained where the normally guided needle thread between the thread clamp 40 and the needle bar tension 39 is partly collapsed substantially at the rate at which the needle on its first descent uses up the resulting thread slack, and the extra needle thread drawn from the thread supply is released to the needle substantially at the rate required by the latter during its continued descent, with the result that the thread in the machine is at no time appreciably slackened and is always under the full control of the stitch-forming instrumentalities. Actual tests on a machine of this type have shown that, on properly adjusting the arm 50 and member 55 and by using a cam 71 of proper design, no thread is withdrawn through the eye of the needle during the first descent of the same, except a negligible length during the very last part of the needle descent after the clamp 40 is closed and the thread tensioned to assure the casting of a loop by the needle on its following ascent. Thus, the thread was marked with a pencil at the needle eye, and the pencil mark on the thread did not shift relative to the needle eye in any of the needle positions shown in Figs. 6 to 9, inclusive, while the thread in the machine was at the same time observed to be substantially taut.

I claim:

1. In a sewing machine, the combination with a reciprocating needle and three successive

thread tensioning devices of which one endmost device is movable with the needle and the intermediate device is a thread clamp operable to grip and release the needle thread, of mechanism providing a thread guide between a first pair of devices consisting of said endmost and the intermediate devices and a thread pull-off between a second pair of devices consisting of said intermediate and the other endmost devices, said mechanism being movable in one direction to slacken the thread between said first pair of devices and to draw extra needle thread from a thread supply between said second pair of devices while said clamp is closed, and also movable in the opposite direction to cooperate with the descending needle in drawing said extra thread between said first pair of devices while said clamp is open.

2. The combination in a sewing machine as set forth in claim 1, in which said thread guide and pull-off are relatively adjustable.

3. In a sewing machine, the combination with an eye-pointed needle, means to reciprocate the same including a drive shaft, and successive thread tensioning devices between said needle and a needle thread supply of which an endmost device is movable with said needle, of mechanism to guide the needle thread between said devices, said mechanism being movable from a certain position to slacken the thread between two successive devices of which one is said endmost device and to draw extra needle thread from the supply through another of said devices, and also movable into said certain position to cooperate with the descending needle in drawing said extra thread between said two successive devices, and a cam on said drive shaft for moving said mechanism from and into said certain position while the needle descends such that the thread between said two successive devices remains substantially taut and the length of the thread end extending from the needle eye remains unchanged substantially throughout said needle descent.

4. In a sewing machine, the combination with a needle, means to reciprocate the same including a drive shaft making one revolution for each needle reciprocation, and successive thread tensioning devices between said needle and a needle thread supply of which an endmost device is movable with said needle, of movable mechanism to guide the needle thread between said devices, said mechanism being normally urged from home position into another position to slacken the thread between two successive devices of which one is said endmost device and to draw extra needle thread from the supply through another of said devices, and movable back into home position to cooperate with the descending needle in drawing said extra thread between said two successive devices, a releasable latch arresting said mechanism in home position, and a cam on said drive shaft engaged by said mechanism on slight movement of same from home position into an intermediate position, said cam being adapted during one revolution to control movement of said mechanism from said intermediate position into said other position and then cause movement of said mechanism back into home position.

5. In a sewing machine, the combination with a work support, a liftable work clamp, a needle, means to reciprocate said needle including a drive shaft making one revolution for each needle reciprocation, and successive thread tensioning devices between said needle and a needle thread

supply of which an endmost device is movable with said needle, of movable mechanism to guide the needle thread between said devices, said mechanism being normally urged from home position into another position to slacken the thread between two successive devices of which one is said endmost device and to draw extra needle thread from the supply through another of said devices, and movable back into home position to draw said extra thread between said two devices, a movable latch adapted, when in operative position, to arrest said mechanism in home position, a cam on said drive shaft engaged by said mechanism on slight movement of same from home position into an intermediate position, said cam being adapted during one revolution to control movement of said mechanism from said intermediate position into said other position and then cause movement of said mechanism back into home position, and means to withdraw said latch from operative position on lifting said work clamp and to return said latch into operative position on lowering said work clamp.

6. In a sewing machine, the combination of a reciprocating needle bar, a needle carried thereby, a releasable normally closed thread clamp disposed between the needle and a thread supply, a reciprocating tension operative to draw slack thread toward the work while the clamp is closed, and a movable device between the thread clamp and needle operative when the clamp is closed to give up thread to the reciprocating tension as the needle moves toward the work.

7. In a sewing machine, the combination with a reciprocating needle, a thread tension movable with said needle and a releasable thread clamp between a thread supply and said tension, of a device normally positioned to guide the thread from said clamp to said tension, said device being movable from its normal position to slacken the guided thread so as to supply part of it to said tension when said clamp is closed, and returnable to its normal position to cooperate with the descending needle in drawing thread through said clamp while the latter is released.

8. In a sewing machine, the combination with a reciprocating needle, a thread tension movable with said needle and a releasable thread clamp between a thread supply and said tension, of a device normally positioned to guide the thread between said tension and thread supply, said device being movable from its normal position to

draw extra thread from said supply, and simultaneously slacken the thread between said clamp and tension so as to supply part of it to said tension, when said clamp is closed, and returnable to its normal position to cooperate with the descending needle in drawing said extra thread through said clamp while the latter is released.

9. The combination in a sewing machine as set forth in claim 8, in which said device comprises a thread guide between said clamp and tension and a thread pull-off between said clamp and thread supply.

10. In a sewing machine, the combination with stitch-forming mechanism including a reciprocating, eye-pointed needle, a thread tension movable with said needle, a releasable thread clamp between a thread supply and said tension, and means for operating said mechanism through a sewing cycle, of a device normally positioned to guide the thread between said tension and thread supply and being moved in timed relation with said operating means, first from its normal position and while said clamp is closed to draw extra thread from said supply and simultaneously slacken the thread between said clamp and tension so as to supply part of it to said tension when, and at the rate at which, said needle requires thread during a part of its first descent in a sewing cycle without withdrawing thread through the 25 needle eye, and then back to its normal position to cooperate with the needle, still on its first descent, in drawing said extra thread through said clamp while the latter is released.

11. The combination in a sewing machine as set forth in claim 10, in which said device draws extra thread of an amount to replenish the thread between said tension and clamp on movement of said device into its normal position, and to supply said tension with the thread required by the 40 needle substantially for the remaining part of its first descent in a sewing cycle without withdrawing thread through the needle eye.
